UNITED STATES PATENT OFFICE.

ALFRED D. TINGLEY, OF NEW YORK, N. Y.

FEED-BOX FOR STOCK.

SPECIFICATION forming part of Letters Patent No. 268,150, dated November 28, 1882.

Application filed May 2, 1882. (No model.)

To all whom it may concern:

Be it known that I, ALFRED D. TINGLEY, a citizen of the United States, residing at New York, in the county of New York and State of New York, have invented certain new and useful Improvements in Feed-Boxes for Stock; and I do hereby declare the following to be a full, clear, and exact description of the invention, such as will enable others skilled in the art to which it appertains to make and use the same.

My present invention constitutes one of a series of modifications or improvements in devices for feeding and watering stock in cars in transitu set forth in Letters Patent granted to me February 8, 1881, No. 237,641; and it consists of a flexible reversible feed and watering cup or box and means for operating the same, by which stock can be watered and fed while in the car without requiring any change whatever in the form or construction of the ordinary stock-cars now in general use.

The improvement is illustrated in the accompanying drawings, in which Figure 1 is a perspective view of the same, showing its appearance and position when located along the side of a track and on one side of car; and Fig. 2, a detail view.

My present form of feed-boxes may be used in connection with a swinging frame and its attachments, which form the subject of another application for Letters Patent filed by me March 25, 1882. In the present application, however, the form of frame is different, and there is only retained the idea of the independent lateral and vertical movement of the feed-boxes, the means of connecting the water-pipe with the feed-cups by separate flexible pipes, and the cut-off mechanism.

A A represent posts located at a convenient position along either side of a car-track, which are firmly planted in the ground or on a suitable platform or supports and securely braced, and on which are rigidly mounted a central rod, D, and an upper main water-pipe, I.

L represents my present form of feed-box, which is composed of stout canvas drawn over and fastened around a flat metallic rim, m. This rim may be made of gas-pipe; but I prefer the flat form.

O is a gas-pipe handle screwed into or through

the metallic rim, or bolted, as shown, to and between the ends of the metallic rim m. At their outer ends the rods O are provided with hand-holds s to assist in the manipulation of the feed-boxes.

H represents a block arranged to slide on center rod, D, and held thereon by hoop-bands i i. It is provided with a lateral central slot, in the outer end of which is pivoted a cam-lever, l, and also with a grooved loose block, p, held within the slot by the cam-lever and one of the bands i. The handle O is passed through this slot, which is grooved at its rear end to conform to the contour of the handle and confined to its place in said slot by the pressure of cam-lever l on block p. The cam-lever is made to fit with sufficient tightness in the block that when pressed against block p it will hold the handle O in place without further means of restraint. The cam-lever is also shown provided with a small hole at its outer end for the insertion of the bent end of a suitable handle, so that the lever can be operated by an attendant standing at the side of the frame. The under side of the block H is also grooved to bear upon the central rod, D. The space between the under side of the block and the bands i is made sufficiently great to permit the blocks to be given a rolling motion, so that the handles O and feed-boxes can be tipped up or down, as may be necessary in pushing the feed-boxes in and out between the slats at any height.

C and E are rests for the feed-box handles, mounted on suitable supports, 1 2 3 4. C and E are situated at a distance from and a number of inches lower than the central rod in order to support the feed-boxes when they are pushed into a car at points lower or higher than the central rod. The feed-boxes are provided with overflow-pipes r, running through the rim m, which, when the boxes are pushed into the car, will extend outside of the car and permit the overflow of water to run out of the car instead of in it, thus keeping the car dry.

I is a main water-conducting pipe extending the whole length of the frame and held in brackets on the top of posts A, and attached to said pipe and leading to the feed-boxes are supplementary flexible pipes t, as and for the purpose described in my previous patent.

When it is desired to use a portion only of the water-cups the water can be cut off from the remaining ones by the use of a cut-off, R, located at the junction of each flexible pipe with 5 the main pipe.

When it is desired to feed the stock several quarts of feed are placed in each of the boxes L, (but not enough to fill it to its utmost capacity,) which, by reason of the flexible material of the box, can then be pushed through 10 between the slats of an ordinary stock-car without spilling any of the contents, and carried directly under the head of the animal to be fed. The box and handle are then held securely 15 in place by swinging the lever l against the block p. When it is necessary to water the stock lever l is released, the feed-box handle turned, which reverses the flexible box L, and water is admitted from main conducting- 20 pipe and flexible pipes. As some animals refuse to drink water contaminated with feed, a supply of clean pure water is thus provided. It is apparent, however, that these flexible 25 boxes can be used both for feeding and watering, if desired, without reversing the same, in which case the locking mechanism can be dis-

pensed with, and a lateral sliding block with simply an aperture through it to accommodate the movement of the handle can be used, as shown in my pending application before men- 30 tioned.

Having thus described my invention, what I claim, and desire to secure by Letters Patent, is—

1. In a stock-car feeding device, the sliding, 35 flexible, and reversible feed and water box, substantially as described.
2. The combination of said flexible feed-box with sliding block H, provided with lever l and block p, substantially as described. 40
3. The combination of flexible feed-box and handles, the lateral independent moving and rolling or tilting support-blocks and their supports, the main water and conducting pipe, and the flexible connecting-pipes, substantially as 45 described.

In testimony whereof I affix my signature in presence of two witnesses.

ALFRED D. TINGLEY.
